Fraser, Frank & Myers

UNITED STATES PATENT OFFICE.

DAVID BRATTER, OF NEW YORK, N. Y.

MOLD FOR CONCRETE COLUMNS.

1,250,956.

Specification of Letters Patent. Patented Dec. 25, 1917.

Application filed June 12, 1917. Serial No. 174,193.

To all whom it may concern:

Be it known that I, DAVID BRATTER, a subject of the Emperor of Austria, having declared my intention of becoming a citizen of the United States of America, residing in the borough of the Bronx, county of Bronx, city and State of New York, have invented certain new and useful Improvements in Molds for Concrete Columns, of which the following is a specification.

This invention relates to molds for concrete columns and aims to provide improvements therein.

The tamping which the material in concrete molds receives requires that such molds, and especially their fastenings, should be stoutly made. Moreover, the plastic nature of the material placed in the molds frequently has objectionable effects in clogging up parts of the fasteners, as, for example, the screwthreads upon parts of fasteners.

The present invention provides a mold for concrete columns, which is well adapted to stand the strains incident to the work, which may be put up and taken down with a minimum of effort and time, which may be very simply constructed, and the parts of which are not seriously affected by becoming smeared with the plastic cement or concrete, and which, moreover, requires the use of the simplest tool, viz: a hammer, in erecting it and taking it down.

An embodiment of the invention is illustrated in the accompanying drawings, and the invention will be more fully explained in connection with said drawings.

In said drawings—

Figure 1 is a view in elevation of part of a mold for a concrete column, parts being broken away and shown in section;

Fig. 2 is a transverse sectional view on the line II—II, Fig. 1;

Fig. 3 is a vertical sectional view on the line III—III, Fig. 1;

Fig. 4 is a view in elevation of parts of the mold.

The mold is preferably made in two longitudinal sections 1—1, being preferably formed of sheet metal, and having angle iron strips, 2—2 riveted thereto at their longitudinal edges. The inside of the mold is preferably countersunk at the riveted holes, so that the rivets may be flush with the inside of the mold, as indicated at 3, Fig. 3.

The mold may also have extensions at one or both ends, the extension, or extensions, comprising longitudinal half-portions 4—4, similar to the portions 1—1. The portions 4—4 are preferably provided at their edges with angle iron strips 5—5 similar to the strips 2—2.

The angle iron strips 2—2 and 5—5 are provided with a series of holes or apertures 6—6, the holes in one strip being opposite the holes in the other. Through these holes 6 are passed keys 7. These keys are of metal and are simply pushed through the holes, with the aid of a hammer, if necessary. The keys 7 are preferably provided with heads 8 to prevent them passing entirely through the holes 6. The keys 7 are provided with slots 9, and through these slots 9 are passed wedge pieces 10. These wedge pieces, in conjunction with the keys 7, hold the strips 2—2 and 5—5 together, and consequently hold the halves of the mold together. To draw the strips 2—2 and 5—5 tightly together, it is simply necessary to tap on the wedge pieces 10 with a hammer. These keys 7 have greater strength than bolts, and the fastening means as a whole have practical advantages over bolts, inasmuch as there are no threads to become clogged with concrete, and, even if the parts 8 are clogged, both the keys and wedge pieces may be readily forced into position with a hammer. Moreover, a hammer is the only tool necessary in connecting and disconnecting the fastening parts of the mold. It is not necessary to use a wrench, as is usual at present. Moreover, the manipulation of fixing the fastening parts 7 and 8 in position, and disconnecting them, is very readily and easily effected, and a great saving of time effected in setting up the molds over molds at present in use.

In order to brace the mold circumferentially, annular braces 14 are provided. These braces 14 are preferably of angle iron and are preferably made in two parts 15 and 16, the parts having projections 17 at their ends. The braces 14 are preferably placed around the parts 1—1 of the mold, and also the parts 4—4 at their top and bottom, and also at suitable places in between, where desired. The portions 17—17 of the brace portions 15 and 16 preferably embrace the upstanding portion of the angle iron strips 2—2 and 5—5. The angle iron strips 2—2 and 5—5

are preferably cut away at their portions which are riveted to the parts 1—1 and 4—4 of the mold, as indicated at 18, in order that the braces may support the mold halves close to their edges. The brace portions 15 and 16 are connected together by keys 7 and wedges 10 passing through holes 20 in the projections 17. The keys 7 and wedges 10 are similar to those used on the strips 2—2 and 5—5. When the braces are fastened in place, they act to hold the strips 2—2 and 5—5 together, as well as to brace the sides of the mold. The grip of the portions 17 of the brace upon the strips 2—2 and 5—5 also acts to fix the braces against displacement on the mold.

The braces 14 at the ends of the mold are preferably provided with a series of holes 23. When an extension is to be used, the main part of the mold and the extension are fastened together by keys 7 which pass through holes 23 in the braces fixed to the adjacent ends of the main part of the mold and the mold extension. The keys are fixed and held in position by wedges 10, as heretofore explained.

It will be seen from the foregoing that the mold is constructed of simple parts, and that the mold may be built up in a very simple manner, and, when put together or built up, the parts are securely held and held in proper position. The fastening parts are very simply and quickly fixed and unfixed.

Modifications may be made in the construction shown and described without departing from the spirit of the invention.

What I claim is:—

1. A mold for concrete columns, said mold comprising a pair of longitudinal halves, an angle iron strip attached at the abutting edges of said longitudinal halves, and angle iron braces adapted to surround said mold halves, said braces being made in two half-portions, the meeting edges of which are turned outwardly and which embrace between them at each side of the mold the outstanding meeting portions of the angle irons attached to the mold halves, and means for fastening the meeting ends of said brace halves together.

2. A mold for concrete columns, said mold comprising a pair of longitudinal halves, an angle iron strip attached at the abutting edges of said longitudinal halves, and angle iron braces adapted to surround said mold halves, said braces being made in two half-portions, the meeting edges of which are turned outwardly, and which embrace between them at each side of the mold the outstanding meeting portions of the angle irons attached to the mold halves, and means for fastening the meeting ends of said brace halves together, said latter means being a slotted key passing through the abutting ends of the brace halves, and a wedge-piece passing through said slot in the key for drawing the parts tightly together.

3. A mold for concrete columns, said mold comprising a pair of longitudinal halves, an angle iron strip attached at the abutting edges of said longitudinal halves, and angle iron braces adapted to surround said mold halves, said braces being made in two half-portions, the meeting edges of which are turned outwardly, and which embrace between them at each side of the mold the outstanding meeting portions of the angle irons attached to the mold halves, and means for fastening the meeting ends of said brace halves together, said braces having slots in the outstanding portions of the angle iron, keys passing through the slots in the outstanding portions of two braces for uniting two braces together and wedges for fastening said keys in place.

4. A mold for concrete columns having abutting edge-portions and means for fastening said edge-portions together, said means comprising flat slotted keys having an inclined edge, said keys passing through said edge-portions and having wedges passing through said slots.

In witness whereof, I have hereunto signed my name.

DAVID BRATNER.
